UNITED STATES PATENT OFFICE

130,072

DESIGN FOR A PIN OR SIMILAR ARTICLE

Lawrence Low, New York, N. Y., assignor to Digby Stores, Inc., New York, N. Y., a corporation of New York

Application August 1, 1941, Serial No. 102,622

Term of patent 3½ years

To all whom it may concern:

Be it known that Lawrence Low, a citizen of the United States and resident of New York, in the county of New York and State of New York, has invented a new, original, and ornamental Design for a Pin or Similar Article, of which the following is a specification, reference being had to the accompanying drawing, forming part thereof, in which

Fig. 1 is a front elevational view of a pin embodying my new design, and

Fig. 2 is a side edge view thereof.

I claim:

The ornamental design for a pin or similar article, substantially as shown.

LAWRENCE LOW.
